UNITED STATES PATENT OFFICE.

EDWARD H. ULLNER, OF WOODCLIFF, NEW JERSEY.

SLIDING AND SWINGING SASH-WINDOW.

SPECIFICATION forming part of Letters Patent No. 772,686, dated October 18, 1904.

Application filed May 5, 1904. Serial No. 206,441. (No model.)

To all whom it may concern:

Be it known that I, EDWARD H. ULLNER, a citizen of the United States, residing in Woodcliff, in the county of Hudson and State of New Jersey, have invented certain new and useful Improvements in Sliding and Swinging Sash-Windows, of which the following is a specification.

This invention relates to an improved sash-window which is provided with the usual lower and upper sashes, each sliding vertically in its grooves, and with a pivoted window-frame for said sashes, by which the sashes can be moved inwardly into the room, so as to permit the convenient cleaning of the window at both sides without requiring the person cleaning the sashes to sit on the window-sill and to lean outside of the window.

For this purpose the invention consists in placing in the stationary or main window-frame, which is set into the wall of the building, a secondary frame, that is pivoted at one side to the main frame and provided with an upper and a lower sash guided vertically in the usual guide-grooves arranged in the secondary frame, said secondary frame being rounded off at that side which is pivoted to the main frame, so as to permit of its being swung into open position, in connection with a suitable locking device arranged at the opposite side of the secondary frame and a knob or other handle device for operating the secondary frame when opening or closing the same.

The invention consists, further, in the combination, with said secondary frame, of an upper and a lower sash guided in the same, each sash being suspended by a sash-weight at one side in the usual manner and provided at its lower corner and at its upper diametrically opposite corner with a guide-roller for permitting the easy up-and-down motion of the sashes by the action of one weight for each sash.

The invention consists, further, in certain details of construction, such as the tight fitting of the secondary frame in the main frame and in the pivot connection of one side of the same with the main frame, and, lastly, in other details of construction and combina-

tions of parts, which will be fully described hereinafter and finally pointed out in the claims.

In the accompanying drawings, Figure 1 represents a front elevation of my improved sliding and swinging sash-window. Fig. 2 is a horizontal section on line 2 2, Fig. 1. Fig. 3 is a vertical transverse section on line 3 3, Fig. 1. Fig. 4 is a detail horizontal section through one jamb of the sash-window and its main frame, taken on line 4 4, Fig. 1. Fig. 4^a is a detail horizontal section on line 4^a 4^a, Fig. 1. Fig. 4^b is a detail vertical section on line 4^b 4^b, Fig. 4^a. Fig. 5 is a detail end elevation of the upper part of the secondary frame, showing the action of the sashes with one sash-weight only for each sash. Fig. 6 is a horizontal section on line 6 6, Fig. 5. Figs. 7 and 7^a are respectively a side and end elevation of the detachable panel for closing the space at the end of the secondary frame. Fig. 8 is a detail end elevation of the lower portion of the sash, showing its connection with the sash cord or chain and an antifriction-roller at its lower corner. Fig. 9 is a detail front elevation of Fig. 8. Figs. 10 and 11 are horizontal sections, respectively on lines 10 10, Fig. 8, and 11 11, Fig. 9; and Figs. 12 and 13 are respectively a detail side view and a plan view of the pivotal connection of the secondary sash-frame with the main frame of the sash-window.

Similar letters of reference indicate corresponding parts.

Referring to the drawings, A indicates the main frame of my improved sash-window, said main frame being made in the usual manner and inserted into the opening left in the wall for the sash-window. To the sill *a* and to the upper portion of the main frame A is pivoted at one side a secondary frame B, said secondary frame being accurately fitted into the main frame A and provided at its upper and lower ends with pivots *b*, each pivot being provided with a plate *c*, that is attached by screws to the upper and lower corners of the secondary frame B, said pivots *b* turning in sockets *b'*, that are set into the mortises of the main frame A and secured rigidly thereto by means of fastening-screws passing through

the flanges b^2 of the socket. By thus pivoting the secondary frame B into the main frame A the secondary frame can be readily swung into open or closed position, the secondary frame B being for this purpose rounded off at the end adjacent to the pivot b , the rounded-off portion h being made concentric with the axis passing through the pivots b , while the horizontal portions and the opposite vertical end or jamb of the secondary frame B are fitted into the main frame A so as to produce a tight joint therewith. The secondary frame B is provided at the jamb opposite to its pivoted jamb with a knob h and locking member k' , so as to permit the convenient opening or closing of the secondary frame B out of or into the main frame A.

The secondary frame B is provided with the usual guide-grooves c' for the sashes C and D. 20 The meeting-rails m of the sashes C and D can be secured by any approved sash-fastener, if desired; but it is preferable to dispense with the ordinary sash-fastener and use in place thereof a sash-lock such as shown in Figs. 1 and 2. The sash-lock is provided with a spindle s^3 , having a handle k^3 at its outer end, and two bolts c^3 , which are thrown forward or backward simultaneously by the turning of the spindle, so as to engage when in thrown position a socket in the end of each meeting-rail of the sashes, as shown in Figs. 4^a and 4^b, and thereby lock the sashes in such a manner that they cannot be tampered with from the outside when the bolts are in locked position. When the bolts are thrown back, the sashes are free to move in the secondary frame B in the same manner as in the ordinary sashes.

Each sash is provided at the jamb, adjacent 40 to that side pivoted to the main frame A, with a sash cord or chain d and weight d' , the cord or chain being placed in a groove d^3 in the jamb of the sash and retained in a socket d^3 in the lower end of said groove by means of a knot l in the cord d and a washer g , placed above said knot l , as shown in Figs. 8 and 9. By arranging the sash-cords d in grooves in the ends of the sashes C and D very little space is required for the sash-weight d' , the sash-cords d being guided over pulleys d^5 , that are arranged in the upper part of the jamb of the secondary frame B, as shown in dotted lines in Fig. 1 and in full lines in Fig. 5. The rounded-off end h of the secondary frame B is provided adjacent to the sash-cords d and weights d' with detachable panels p , that are retained by cross-pieces p' , which are attached to the rounded-off end of the secondary frame B, as shown in Fig. 5, the panel p being provided with an opening p^2 , so as to permit the convenient taking hold of said panel, so as to readily remove the same from the secondary frame B when it is desired to get to the sash-cords d for inserting a new cord or for other 60 repairs. The panels p are provided with

shoulders p^3 at their upper and lower ends, so as to rest on the cross-pieces p' . For facilitating the easy and frictionless up-and-down motion of the sashes C and D and in order to distribute the lateral strain due to the arrangement of the counterbalancing - weights at one side only of the sash each sash is provided at its lower corner, below the socket d^5 for the sash-cords d , with an antifriction-roller f , the spindle f^3 of which is supported in ears of a cast-metal plate f' , that is attached by wood-screws to the lower corner of each sash, so as to retain the antifriction-roller f in position in such a manner that it projects slightly beyond the jamb of the sash and forms contact with the guide-groove c' of the secondary frame B. Each sash is also provided at a point diametrically opposite to the friction-roller f with a second antifriction-roller f^2 , which is supported in a recess of the sash-frame and which moves, in connection with the opposite guide-groove c' , in the secondary frame B, the two rollers f and f^2 , in connection with the single sash-cord d and weight d' , permitting the moving up and down of each sash in a perfectly easy and noiseless manner by the use of a sash-weight at one side only—namely, at the side adjacent to the pivoted portion of the secondary frame B—so as to dispense with the use of sash-weights d' at the opposite side of the secondary frame B, where owing to the necessity of opening and closing the secondary frame B they could not be arranged. By means of antifriction-rollers f and f^2 and sash-weights d' arranged at one side only the pivoting of the secondary frame B at one side and the convenient opening and closing of the same in the main frame A are permitted, so as to give convenient access to the sash-panels p from opposite sides for cleaning, repairing, &c., without sitting on the window-sill and leaning out of the window, as in the case of the present sash-windows. By swinging the secondary frame B into open position the entire window-opening can be used for purposes of ventilating, moving large objects in or out of the window, and facilitating the easier egress in case of fire and the easier ingress of firemen.

It is obvious that in place of the locking device for the sashes described any suitable locking device may be used, also any suitable mechanism for attaching the sash-cords to the sashes, as I do not desire to confine myself to the construction shown in the drawings. It is further obvious that for producing a tight fit of the secondary frame B in the main frame A the lower part or sill of the secondary frame B is provided with rabbeted ledges y , that project over correspondingly-raised portions of the main frame A, so as to produce an air and water tight fitting of the secondary frame B. It is also necessary that the front projecting lip t of the secondary frame B be

recessed at its upper and lower edge adjacent to the pivoted end of the secondary frame, as shown at *r*, so as to permit the swinging of the same into open position without being interfered with by the projecting ledges, as shown in the right-hand side of Fig. 1.

My improved sash-window is adapted for all apartment-houses and very tall buildings owing to the danger connected with the cleaning of windows or replacing broken panes of glass. The window is also adapted for first-floor windows, for the reason that the locking devices of the sashes can be less interfered with than the ordinary sash-fasteners heretofore in use. While, on the one hand, my improved window is slightly increased in cost owing to the arrangement of the secondary frame, the cost is diminished, on the other hand, for the reason that the sash-boxes required for the present windows are dispensed with. For some purposes, when large objects have to be removed into the building, the extra space can be obtained by removing the secondary frame, with the sashes, bodily by unscrewing the pivot of the same, so that the clear opening of the entire inside height and width of the main frame is available, which is of considerable advantage in many cases.

Having thus described my invention, I claim as new and desire to secure by Letters Patent—

1. The combination, in a sash-window, with a window-frame having upper and lower sashes slideable therein, said sashes being provided with longitudinal grooves in one side 35 jamb, of pulleys at the upper end of one jamb, sash-cords attached to the lower end of said grooves, counterbalancing-weights applied to the opposite ends of the sash-cords, an anti-friction-roller at the lower end of each sash 40 below the sash-cord connection, and an anti-friction-roller at the diametrically opposite corner of each sash near the upper end of the same.

2. In a sash-window, the combination, with 45 a main frame, of a secondary frame pivoted at one side to the main frame, sashes slideable in said secondary frame, the latter having a groove at the side in proximity to the pivot, counterbalancing-weights attached to said 50 sashes and movable in said groove, cross-pieces at the terminal portions of said groove, and a removable covering-panel retained by said cross-pieces.

In testimony that I claim the foregoing as 55 my invention I have signed my name in presence of two subscribing witnesses.

EDWARD H. ULLNER.
